[57] CLAIM

The ornamental design for a mammographic accessory, as shown.

DESCRIPTION

FIG. 1 is a front perspective view of a first form of a mammographic accessory embodying my new design; FIG. 2 is a side elevational view thereof illustrating the left side of FIG. 1, the opposite side being a mirror image thereof;

FIG. 3 is a front elevational view thereof;

FIG. 4 is a rear elevational view thereof;

FIG. 5 is a top plan view thereof;

FIG. 6 is a bottom rear view thereof;

FIG. 7 is a front perspective view of a second form of a mammographic accessory embodying my new design; FIG. 8 is a side elevational view thereof illustrating the left side of FIG. 1, the opposite side being a mirror image thereof;

FIG. 9 is a front elevational view thereof;

FIG. 10 is a rear elevational view thereof;

FIG. 11 is a top plan view thereof; and,

FIG. 12 is a bottom plan view thereof.
